UNITED STATES PATENT OFFICE.

NELSON T. VELIQUETTE, OF KEWADIN, MICHIGAN.

COMBINED GUN-CASE AND AMMUNITION-BELT.

No. 873,140.

Specification of Letters Patent.

Patented Dec. 10, 1907.

Application filed June 27, 1906, Serial No. 323,674. Renewed September 16, 1907. Serial No. 393,117.

To all whom it may concern:

Be it known that I, NELSON T. VELIQUETTE, a citizen of the United States, residing at Kewadin, in the county of Antrim, 5 State of Michigan, have invented certain new and useful Improvements in a Combined Gun-Case and Ammunition-Belt; and I do hereby declare the following to be 10 invention, such as will enable others skilled in the art to which it appertains to make and use the same.

This invention relates to combined gun cases and ammunition belts and has for its 15 object to provide an extremely simple device of this character which may be manufactured at a low cost and which will not be cumbersome.

A further object of the invention is to provide 20 an article of this class including a shoulder strap and further resides in connecting the ends of the strap to the case at equi-distant points from the ends of the series of cartridge loops. As the major portion 25 of the weight is on this portion of the device when in use as a belt, it will be seen that by connecting the strap with the belt in this manner, the weight will be evenly distributed.

With the above and other objects in view, 30 the present invention consists in the construction and arrangement of parts, shown in the accompanying drawings:

Figure 1 is a side elevation of the case. 35 Fig. 2 is a similar view showing the same when in use as a belt, and, Fig. 3 is an end view showing the manner of folding the gun stock containing portion of the case when in use as a belt.

The case as shown, is designed to contain a 40 gun having a rigidly connected stock and barrel, the portions of the case for the reception of these parts of the gun being indicated by the numerals 5 and 6 respectively. One 45 of the sides of the stock end of the case is provided with the usual flap closure 7 which is provided with the ordinary strap 8 for engagement with a buckle 9 carried by the other side of the case at the corresponding 50 end.

Permanently secured to that side of the portion 6 of the gun case upon which the flap

7 is located is a cartridge supporting strip comprising the usual series of loops 10 and the said strip extends from a point adjacent 55 the end of the portion 6 to a point slightly beyond the junction of the portions 5 and 6.

In order that the case may be used as a belt and secured around the waist of the user, I secure upon that side of the portion 5 of the 60 casing from which the flap 7 extends, a strap 11 which is designed for engagement with a buckle 12 upon the corresponding side of the portion 5 of the casing and intermediate the end of the same and the adjacent end of the 65 loop series 10. When used as a belt, the portion 5 of the casing is folded upon itself along the dotted lines 12' indicated in Fig. 1 and as shown in Fig. 2, to lie against the opposite side of the casing to that upon which the loop 70 series 10 is located. It will be noted that by folding the casing in this manner, the buckle 9 and strap 8 will be covered by the folded portions and will not injure the clothing of the hunter. 75

In order that the weight of the belt may be partially sustained by the shoulders, I provide a shoulder strap 13 which is secured at its ends to the portion 6 of the case, at equi-distant points from the ends of the loop series 80 10, in this manner equally distributing the weight.

It is to be understood that I do not desire to be limited to the exact details of construction shown and described, for obvious modifications will occur to a person skilled in the art. 85

What is claimed is:

1. A gun case including a barrel inclosing portion and a stock inclosing portion, a series of cartridge loops secured upon its barrel inclosing portion and extending substantially throughout the entire length thereof, the stock inclosing portion of the gun case being foldable upon itself to form a belt portion which constitutes a continuation of the barrel inclosing portion and is substantially the same width as the barrel inclosing portion, and a strap carried by the stock inclosing portion. 95

2. A gun case including a barrel inclosing portion and a stock inclosing portion, a series of cartridge loops secured upon its barrel inclosing portion and extending substan- 100

tially throughout the entire length thereof, the stock inclosing portion of the gun case being foldable upon itself to form a belt portion which constitutes a continuation of the barrel inclosing portion and is substantially the same width as the barrel inclosing portion, a flap carried by the stock inclosing portion, and straps secured one to the stock inclosing

portion and the other to the end of the flap thereof as and for the purpose stated.

In testimony whereof, I affix my signature, in presence of two witnesses.

NELSON T. VELIQUETTE.
